UNITED STATES PATENT OFFICE.

CARL DEBUYSÈRE, OF STUTTGART, WÜRTEMBERG, GERMANY.

FINGER-EXERCISING DEVICE.

SPECIFICATION forming part of Letters Patent No. 336,216, dated February 16, 1886.

Application filed December 22, 1884. Serial No. 150,959. (No model.) Patented in France December 3, 1884, No. 165,741; in Germany December 4, 1884, No. 31,763, and in England April 11, 1885, No. 4,501.

To all whom it may concern.

Be it known that I, CARL DEBUYSÈRE, engineer, a subject of the King of Würtemberg, residing at Stuttgart, Würtemberg, German Empire, have invented certain new and useful Improvements in Apparatus for Training Fingers for Musical Instruments; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention has for its object to provide means whereby the flexibility of the joints of the fingers of pupils or performers on the piano and other key-board instruments is developed in a more rapid manner than could be done by practice on the instrument itself; and the said invention consists in a machine or apparatus for obtaining the above-recited results, substantially as hereinafter fully described, and as specifically set forth in the claims hereto annexed.

Referring to the accompanying drawings, Figure 1 is a vertical longitudinal section of my apparatus. Figs. 2 and 3 illustrate the same by a top plan view and a front elevation, respectively. Fig. 4 is a detail view, on a larger scale, showing two of the keys in side elevation and the actuating-drum in section. Fig. 5 is a top plan view of one of the keys, also on an enlarged scale. Figs. 6 and 7 are sectional elevations of a part of the apparatus, illustrating modified arrangements of the actuating-drum. Figs. 8, 9, and 10 are detail views illustrating the construction and mode of pivoting the thimbles. Fig. 11 is a part of the periphery of the actuating-drum, illustrating the form of the slots for the cam-blocks. Figs. 12, 13, and 14 are respectively a side view, an under side view, and a transverse section of one of the cams; and Figs. 15 and 16 are detail perspective views of the clamping devices for holding the hand of the pupil.

In the above-described figures of drawings like letters of reference indicate like parts. The apparatus is supported from a suitable stand, *s*, the top *B* of which constitutes the

base-plate from which the operating mechanism is supported, and on which said mechanism is longitudinally adjustable. A shaft, *S*, mounted below the table-top *B*, carries a fly-wheel, *W*, and a belt or cord pulley, *P*, operated by crank, connecting-rod, and treadle, like a sewing-machine, and serves to impart motion to the levers of the apparatus, as hereinafter described.

To prevent backward movement of the fly-wheel, I employ a brake consisting of an eccentric rubber disk, *w*, pivoted in a suitable bracket in proximity to the wheel, or, if desired, the usual ball-brake employed on sewing-machines may be applied to the wheel *W*.

Upon the table-top *B* is arranged a board, *K*, that here serves the purposes of a key-board, from the lateral edges of which project cheeks or side pieces, *k*, in which are mounted two shafts, *S'* and *S*. The shaft *S'* carries a drum, *D*, to which are secured blocks or cams *C*, for purposes presently explained; and said shaft also carries a belt or cord pulley, *P'*, belted to pulley *P* on driving-shaft *S*. The actuating blocks or cams *C* may be secured to the drum *D* by means of screws, and adjusted thereon, as desired, relatively to the rhythmic movement to be imparted to the levers by means of the special construction of drum and cams. This adjustment is, however, greatly facilitated. The drum *D*, as shown in Figs. 2, 3, 4, and 11, is provided with a series of slots, *D'*, formed in parallel rows in its periphery, the diameter of the slots being greater at one end thereof, and at the opposite end the cams *C* have on their under side a double-T projection, *C'*, the stem *c* of which fits the narrow portion *d* of the slots *D'*, and the cross-bars *c'* the wider portion *d'* of said slots. It is obvious that when the projection *C'* of a cam is inserted into a slot, *D'*, of the drum and then moved to the narrow portion *d* at one end of the slot, said projection will interlock the cross-bars *c'*, lying across the narrow portion *d* of said slot.

To prevent the accidental displacement of the cams, I apply thereto a spring, *c*, the free end of which, when the cam is properly locked to the drum, bears against the forward edge of the slot, or that edge which faces in a direction opposite to that of the motion of the

drum, so that when the cams impinge upon the lever ends the pressure will be exerted upon the edge of the slot which faces the direction of motion, thereby insuring the retention of the blocks in proper position.

On shaft S^2 are loosely mounted any desired number of levers L , that serve the purposes of the ordinary keys, the short arms l of which lie in the path of the cams C on drum D .
 16 The lever-support also carries the mechanism for securing the hand of the pupil, and said support, together with all the operative devices of the apparatus, is adjustable longitudinally on the table-top B by means of a set-screw, b , that passes through a slot, b' , in said table-top and carries a winged nut, b^2 .

The object of making the key-board adjustable, as described, is to provide a ready means for regulating the tension of the belt or cord c^2 , as it is evident that the latter may be tightened or slackened by moving the board K forward or backward, thereby decreasing or increasing the distance between the axes of the belt-pulleys $P P'$. The short arms l of the levers L may be appropriately shaped—that is to say, their upper faces made concave to correspond with the convex form of the cams C on drum D . In practice I prefer, however, to provide a separate block, L' , connected with lever-arm l by a dovetail joint, as shown in Fig. 1, or by means of a screw, l' , as shown in Fig. 4.

By the described arrangement of blocks I provide a means whereby any wear in the short arm of the levers L may be readily compensated by inserting a new block at trifling expense, instead of having to replace the lever by a new one. The downward movement of the long arm of the levers L is limited by a rail, R , that extends entirely across the board K , and to avoid the noise resulting from the impact of the levers with said rail I preferably cover the top thereof with flannel or upholstering r , as shown. This downward movement of the long arm of the levers is in practice made variable, in order to give to the fingers of the pupil a greater range of motion or articulation. This is effected by means of rails R of various elevations, said rails being interchangeable and adapted to be secured to the board K , or the cheeks thereof, in any suitable manner. For instance, each rail may be provided with two or more pins, r' , adapted to fit into holes or recesses formed in the board K ; or said rails may be secured to the cheeks k of said board by means of a screw or pin, or in any other manner, so as to adapt the same for ready removal. To the outer end of each lever is secured a thimble, T , into which the end of the finger is placed, said thimbles being articulated and made adjustable in and by the following manner and means, referring more particularly to Figs. 4, 8, 9, and 10:

To the upper face at the outer end of the long arm of the lever L is secured a plate, E , in which is formed a slot, e , and upon said plate is arranged a slide-plate, F , in which is

formed a slot, f , through which passes a guide and set screw, G , the shank of which is screwed into plate E . Through plate F passes an adjusting-screw, A , the head a of which lies in a slot, l^2 , formed in the outer end of the lever and straddles the slot e of plate E .

The adjustment of the slide F along the upper face of lever L may be readily effected by simply unscrewing the milled nut of the adjusting-screw and moving the slide-plate F the required distance and then tightening the same again. The object of this adjustment is to provide a means for varying the distance between the finger ends when inserted into the thimbles T and the hand-rest, hereinafter to be described, according to the length of the fingers of the pupil. The thimbles T are pivoted on a pin, t , that has its bearings in lugs f' , projecting from the slide F , to adapt said thimbles to assume the proper inclination relatively to the first joint of the fingers without cramping the same. In practice this oscillation of the thimbles in the longitudinal axial plane of the keys is, however, not sufficient to avoid the cramping of the fingers, especially those that operate the outer levers, said fingers being in a plane at a greater or less angle to the longitudinal axis of said levers.

To avoid this cramping I arrange the thimbles, especially those on the outer levers, to rotate both on a horizontal and vertical axis, as more plainly shown in Figs. 8, 9, and 10. To this end a segmental plate, p , is countersunk into the upper face of the slide F , said plate being arranged to rotate on a central axis or pivot, p' , that passes through the slide and connects the plate p thereto. To this plate are secured the bearing-lugs f' for the horizontal pivot t of the thimbles T . The vertical rotation of the thimbles is limited by means of a stop-plate, p^2 , against which abut stops on the plate p . The thimbles are provided with a lining of flannel or analogous material.

The means described for adjusting the thimbles longitudinally of the levers L may be modified in various ways. For instance, in Figs. 6 and 7 the slide-plate F has at its rear end a vertical projection, f^2 , that has a screw-threaded opening, in which operates an adjusting-screw, F' , adapted to rotate in bearings e' , formed in a like projection, E' , at the rear end of plate E . It is obvious that by rotating the screw F' in the proper direction the slide F will be moved toward or from the outer end of the lever L .

The levers L , as above stated, are loosely mounted on their shaft S^2 , and may be arranged side by side, as is the case in ordinary key-boards. I prefer, however, to provide means, with a view to employing a less number of levers, for spacing the latter by the interposition of dummies or spacing-blocks, so that the levers may be adjusted to any desired distance from each other. These spacing-blocks B' are of the same width as the levers L , their short arm b^3 being of the same length as the short arm l of said levers, while their

long arm b^4 is considerably shorter than the corresponding arm of the levers. Each spacing-block or dummy has a vertical projection, B, that has at its upper end a rectangular notch, in which fits the shaft S^3 , on which the levers are mounted. The blocks are held against longitudinal displacement during the operation of the apparatus by means of a cross-rail, R^3 , that extends across the row of keys and dummies or spacing-blocks, and has on its under side pins r^3 , that fit into corresponding holes in the board K, as plainly shown in Figs. 1 and 2.

In Figs. 1, 2, 3, and 4 I have shown the drum D arranged above the short arms of the levers L. This, however, is not absolutely necessary, as said drum may be arranged as shown in Fig. 6, the cams acting upon the under side of the long arm of the levers, and said levers may therefore be fulcrumed on shaft S^2 at their rear end.

As shown in Fig. 7, angle-levers may be employed and the drum D arranged so that the cams will act on the short angle-arm of said levers.

To the under side of the short arms l of levers L is secured a rod, R' , to the outer end of which is connected one end of a spring, V, whose opposite end is connected to a rod, R^2 , that has its bearings in a rail or bracket, C^2 , secured to the under side of the table-top or base-plate B. The lower end of the rod R^2 is screw-threaded, and carries a winged nut, r^2 , by means of which the tension of the spring is regulated. This adjustment of the spring is necessary to impart to the levers L the required resistance to downward motion—such as is usually encountered in the keys of pianos or other key-board instruments—and its object is to compel the fingers of the pupil to overcome said resistance the same as if he were exercising on the keys of a piano.

Upon the outer end of the key-board K is arranged a supporting plate or board, H, that is adjustable toward or from the levers L by means of a screw-spindle, h , that operates in a threaded sleeve, h' , secured to plate H. The spindle h is arranged in a slot formed in the outer end of the board K, and is stepped in the rear vertical edge of said slot. The opposite end of the spindle rotates freely in a bearing, h^2 , through which said spindle projects, and upon its projecting end is keyed an operating-crank, h^3 .

As shown at h^4 in Fig. 3, the boards K and H are connected, like a drawer, by tongue-and-groove joint, so as to properly guide the board H and prevent all lateral motion thereof. At each end of the board H is secured a guide-rod, I' , that carries a vertically-adjustable track or slideway formed by two rails or cross-bars, $I I$, whose ends form clamps $i i'$, that embrace the rods I' , to which said rails are secured by clamping-screws $i i$, that pass through their outer ends. Upon the rails I is arranged a carriage, M, adapted to slide thereon, and, when adjusted in the proper po-

sition, to be secured thereto by means of a set-screw, m . A screw-spindle, N, passes through and operates in a threaded opening formed in said carriage M, and carries a block, O, the under face of which is of a curvature approximately that of the back of the hand. The block O is connected with the spindle, so that the former will be free to oscillate on the latter in directions at right angles to each other, as shown in Fig. 15. A socketed link, n , in which the end of the spindle N is secured by means of a set-screw, n^2 , is pivoted to a link, o, and the latter to the block O, their respective pivot-pins, $n' o'$, having their axes in planes at right angles to each other, thus allowing the block O to oscillate in planes at right angles to each other. The range of oscillation of the block, if found desirable, may be increased by connecting the same with the spindle by means of a universal joint.

It will be seen from what has been said that the block O, which constitutes the upper half of the hand-support, has not only movement in two or more directions, but it is adjustable vertically, either through the rails I I on rods I', or by manipulating the spindle N, or both, and laterally on the rails I, so that said block may be adjusted with great nicety relatively to the hand of the pupil. The lower half of the hand support or clamp, Fig. 16, is composed of a block, Q, the upper face of which is convex, the convexity conforming to that of the inner portion of the hand, or approximately so. It is hinged at one end to a board, Q', and in its under side is formed a recess or cavity, q , wherein is arranged an adjusting-screw, q' , whose lower end operates in a threaded opening in the plate Q', while its upper end impinges upon the roof of said cavity. By the described means the inclination of the block Q may be adjusted within certain limits relatively to the inclination the hand is to have when secured in position for practice.

The block Q is, like block O, adjustable both vertically and horizontally in the following manner: The board Q' serves as a carriage, and is adapted to travel along guide-rails U U, secured to the guide-rods I', said rails being constructed and arranged for vertical adjustment on said rods I' by means of clamping-screws u , in the same manner as the rails I, above described. When adjusted, the carriage Q', with its block Q, is locked in position by a screw, U', secured to the under side of the carriage Q'. The screw passes between and projects beyond the rails, and carries a jam-nut, u' , that impinges upon the under side of said rail, as shown in Figs. 1 and 3.

By means of the described arrangement the hand of the pupil may be secured in any desired fixed position relatively to the levers L without interfering with the necessary movements of the hand during the exercise in articulation of the fingers of the pupil, while the block Q may be adjusted on the rails U, for the use of either the right or the left hand, by simply removing the jam-nut u' from screw U',

lifting the carriage Q', with its block Q, off the rails U, and reversing the carriage, as will be readily understood.

The operation of the apparatus, in view of what has been said relatively to its construction and arrangement of parts, may be briefly described, as follows: The cams C are arranged on the drum D according to the exercise in articulation designed for the fingers of the pupil or performer, and the levers L are properly spaced by means of the dummies or blocks B'. The hand of the pupil is next secured in the hand-support O Q, and said support is adjusted to the proper distance from the lever-thimbles to suit the length of the fingers of the pupil, who is seated before the apparatus as he would be seated before a piano. The first joint of the fingers is now inserted into the thimbles T, as shown in dotted lines, Figs. 1 and 4, and the drum D is rotated by means of the pedal or treadle. The rotation of the drum D causes the cams C to impinge on the levers in the order of their relative arrangement, or the rhythmical arrangement of the cams, and elevate said levers every time a cam passes over their short arm, the pupil himself having to overcome the resistance of the springs V to depress the levers, the same as in a piano, whereby a greater muscular suppleness or pliability of the fingers is acquired in a much less time than by practice on the piano. Of course it is understood that the tension of the springs V is not sufficient to elevate the levers with the fingers of the pupil inserted in the thimbles of said levers.

The invention aims especially to the production of an apparatus whereby every possible finger movement required in the performance on key-board instruments can be imparted to the fingers mechanically, and the hand at the same time held in the proper position relatively to movements of the fingers.

By means of the adjustability of the various component parts of the apparatus it is adapted for use by pupils as well as those more advanced in the art of playing, whether they be young or old, as the parts may be adjusted to any size hand or length of fingers.

Having now described my invention, what I claim, and desire to secure by Letters Patent, is—

1. In a finger-exercising apparatus, the combination, substantially as described, of a series of levers provided with a retaining device for the finger ends, a cam-shaft for oscillating said levers, and a driving-wheel for rotating the cam-shaft.

2. In a finger-exercising apparatus, the combination, substantially as described, of a series of levers provided with a retaining device for the finger ends, a cam-shaft for oscillating the levers, a driving-wheel for rotating the cam-shaft, and a rest or support for the hand arranged in front of the levers.

3. In a finger-exercising apparatus, the combination, substantially as described, of a series of levers provided with a retaining de-

vice for the finger ends, a cam-shaft for oscillating the levers, a driving-wheel for rotating the cam-shaft, and a rest or support for the hand, arranged in front of the levers, and adapted for adjustment toward or from the lever ends.

4. In a finger-exercising apparatus, the combination, substantially as described, of a series of levers provided with a retaining device for the finger ends, a cam-shaft for oscillating the levers, a driving-wheel for rotating the cam-shaft, and a rest or support for the hand, arranged in front of the levers, and adapted for adjustment in the plane of the longitudinal axis of the levers, and in planes at right angles thereto.

5. In a finger-exercising apparatus, the combination, substantially as described, of the driving-pulley P, with the cam-shaft S', its driven-pulley P', and the board K, on which said shaft is mounted, said board being adapted for adjustment toward and from the axis of rotation of said driving-pulley.

6. In a finger-exercising apparatus, the combination, substantially as described, of the board K, the levers L, and their shaft S², with the dummies or spacing-blocks B'.

7. In a finger-exercising apparatus, the combination, substantially as described, with the levers L, of hinged thimbles T, adapted to be adjusted longitudinally of the levers for the purpose specified.

8. In a finger-exercising apparatus, the combination, substantially as described, with the levers L, of the removable blocks, L'.

9. In a finger-exercising apparatus, the combination, substantially as described, with the levers L, of the drum D, provided with concentric rows of slots, and teeth or cam projections transferable in said slots, on the periphery of the drum, for the purpose specified.

10. In a finger-exercising apparatus, the combination, substantially as described, with the levers L, of the drum D, provided with peripheral slots D', and the cams C, provided on their under side with a double-T projection, C', and at one end with a spring, e².

11. In a finger-exercising apparatus, the combination, substantially as described, with the levers L, of the hand-support, consisting of the vertically, longitudinally, and laterally adjustable blocks O Q.

12. In a finger-exercising apparatus, the combination, substantially as described, with the lever-support K, of the plate H, the rods I, the rails I U, set-screws i u, the carriages M Q', the blocks O Q, and the clamping-screws m U', said parts being constructed and arranged for operation for the purpose specified.

13. In a finger-exercising apparatus, the combination, substantially as described, with the lever-support K, of the plate H, the rods I, rails I U, carriages M Q', blocks O Q, and the adjusting-screws N q', said parts being constructed and arranged for operation, as described.

14. In a finger-exercising apparatus, the combination, substantially as described, with

the lever-support K, of the plate H, the hand-rests supported thereupon, the threaded sleeve h', and the screw-spindle h, said parts being constructed and arranged for operation for the purpose stated.

15. In a finger-exercising apparatus, the combination, substantially as herein described, with the stand or table, its top B, and the driving-pulley mounted on said stand, of the lever-support K and the hand-rest support H, adjustable jointly on the stand-top toward and

from the axis of rotation of the driving-pulley, and mechanism for adjusting the hand-rest support independently of the lever-support, for the purpose specified.

15
In testimony whereof I affix my signature in presence of two witnesses.

CARL DEBUYSÈRE.
